US00D467188S

(12) United States Design Patent (10) Patent No.: **US D467,188 S**
Lui (45) Date of Patent: **** Dec. 17, 2002**

(54) **WALL PLATE TEMPERATURE AND HUMIDITY SENSOR**

Primary Examiner—Antoine Duval Davis
(74) *Attorney, Agent, or Firm*—Troxell Law Office PLLC

(75) Inventor: **David Ping Lai Lui**, Tai Po (HK)

(57) **CLAIM**

(73) Assignee: **Advanced Timer Technologies, Ltd.**, Kowloon (HK)

The ornamental design for wall plate temperature and humidity sensor, as shown and described.

(**) Term: **14 Years**

DESCRIPTION

(21) Appl. No.: **29/152,225**

FIG. 1 is a top front and left side perspective view of wall plate temperature and humidity sensor showing my new design;

(22) Filed: **Dec. 19, 2001**

FIG. 2 is a front elevational view thereof;

(51) LOC (7) Cl. **10-04**

FIG. 3 is a left side elevational view thereof;

(52) U.S. Cl. **D10/52; D10/57**

FIG. 4 is a right side elevational view thereof;

(58) Field of Search **D10/52, 53, 57;**

FIG. 5 is a top plan view thereof; and,

**73/866.1; 374/170.1, 171.14, 163, 208,
161, 158, 178; 364/571.03, 571.04**

FIG. 6 is a bottom plan view thereof.
